CURTAIN FIXTURE

Filed August 8, 1924

FIG. 1.

FIG. 2.

FIG. 4.

FIG. 5.

FIG. 6.

FIG. 7.

FIG. 8.

Inventor:

John S. Wright,

Attorney.

Witness:

Red L. Fischer.

By

F. G. Fischer,

UNITED STATES PATENT OFFICE.

JOHN S. WRIGHT, OF PLEASANTON, KANSAS.

CURTAIN FIXTURE.

Application filed August 8, 1924. Serial No. 730,895.

To all whom it may concern:

Be it known that I, JOHN S. WRIGHT, a citizen of the United States, residing at Pleasanton, in the county of Linn and State 5 of Kansas, have invented certain new and useful Improvements in Curtain Fixtures, of which the following is a specification.

My invention relates to improvements in fixtures for supporting curtains and draperies, and one object is to provide a fixture of this character having supporting means at its ends adapted to be slipped into position between the wall and a door or window casing for the purpose of reliably holding 15 the fixture in place without the use of nails, screws, or other extraneous fastening devices likely to mar the casing.

A further object is to provide novel supporting means whereon one or more supplemental bars may be supported in addition to the main bar of the fixture, the several parts interlocking in such manner as to prevent accidental dislocation and to successfully resist the vertical stresses to which 25 they are subjected by heavy draperies.

Another object is to provide the fixture with a novel intermediate support to prevent the main and supplemental bars from sagging intermediate their ends beneath the 30 weight of curtains or draperies.

Another object is to provide a fixture that can be adjusted for different sizes of door and window frames, which has comparatively few parts and can be manufactured at 35 relatively small cost.

Other objects will hereinafter appear and in order that the invention may be fully understood, reference will now be had to the accompanying drawing, in which:

Fig. 1 is a perspective view of the curtain fixture in operative position.

Fig. 2 is a plan view of the curtain fixture in operative position.

Fig. 3 is a broken longitudinal section of 45 the main rod or bar and supporting elements associated therewith.

Fig. 4 is a detail perspective view of supporting elements for the main rod or bar and one or more supplemental bars.

Fig. 5 is a cross section on line V—V of Fig. 3.

Fig. 6 is an enlarged cross section on line VI—VI of Fig. 2.

Fig. 7 is a detail side elevation of a supporting member for the intermediate por-

tions of the main and supplemental bars, or rods.

Fig. 8 is a broken detail of one end of one of the supplemental bars, or rods.

Fig. 9 is a broken perspective of one end 60 of a modified form of main bar, or rod.

Referring now in detail to the different parts disclosed by the drawing, A designates the upper part of a door or window casing which is secured to the wall B. 65

2 designates a main member adapted to support a curtain or drapery. Said main member 2 preferably consists of a bar having two sections 4 and 6, adapted to telescope with one another at their adjacent ends, so that 70 they may be adjusted longitudinally for use in connection with a pair of supporting brackets 8 when the same are disposed a greater or less distance apart as may be required by door or window frames of different widths. The outer ends of the bar 2 are formed with elbows 10 the free ends of which extend approximately at right angles to the main portion of said bar.

As shown by Figs. 3 and 5, the edges of 80 each section 4 and 6 are provided with in-turned flanges 12 which are preferably co-extensive with the respective sections and afford telescopic connections between the adjacent ends thereof and also provide sockets 85 at the ends of the elbows 10 for the reception and retention of the brackets 8.

The brackets 8 have inturned blades 14 adapted to be slipped inwardly between the casing A and the wall B and thereby reliably support the main bar 2 and the parts associated therewith. The blades 14 are preferably provided with upward and downward extensions 16 and 18, respectively, to provide a more substantial support for 95 the bar 2 and parts associated therewith, so that they cannot sag at their forward portions.

Clamps 20 slidably mounted in the elbows 10 are provided to engage the face of the 100 casing A and thereby cooperate with the blades 14 in reliably supporting the main bar 2 and the parts carried thereby.

Each bracket 8 has one or more interlocking members 22 extending at right angles 105 thereto as more clearly shown by Figs. 3 and 4. Said interlocking members 22 are provided for the purpose of supporting one or more supplemental bars 24 which are somewhat similar in shape to the main bar 2, ex- 110

cepting that they have no elbows. The outer ends of the telescopic sections 25 and 26 of the supplemental bars 24 are of hollow rectangular cross sectional formation to receive 5 the interlocking members 22 and have lips 28 which extend towards each other and are adapted to interlock with the notched portions 30 of the members 22 whereby the supplemental bars 24 are reliably supported. 10 By providing the outer ends of the sections 24 and 26 with the lips 28, and each interlocking section 22 with two notches 30 to receive said lips care need not be exercised in assembling the fixture as either bracket 8 15 may be placed in either of the elbows 10, while either end of each supplemental bar 24 may engage over any one of the interlocking members 22.

A slight protuberance 31 is formed by a 20 punch, or otherwise, in the section 6 to frictionally engage the section 4 of the bar 2, to prevent undue lateral play between said sections and also to prevent them from accidentally slipping out of telescopic engagement 25 with each other when the fixture is being handled. The supplemental bars 24 may of course be likewise equipped if desired.

In addition to reliably supporting the fixture at its ends by the blades 14 and the 30 clamps 20, I have provided a member 32 for supporting the intermediate portions of the bars 2 and 24, as shown by Figs. 1 and 2. Said supporting member 32 is provided with a blade 34 at its upper portion adapted to be 35 slipped downwardly between the upper portion of the casing A and the wall B and said member 32 is provided with spaced seats 36 open at their upper portions for the reception of the bars 2 and 24.

40 In the modified form of the main bar 2^a disclosed by Fig. 9, the brackets 8 are dispensed with and the ends 2^b are turned towards each other and slotted as indicated at 2^c, so that each may be slipped between a 45 door or window casing and the head of a nail or screw projecting from said casing to support the bar. The inner ends of the slots 2^c are rounded to engage over the body of the nails or screws irrespective of which 50 side of the bar is uppermost.

From the foregoing description it will be apparent that I have provided a fixture embodying the advantages above pointed out, and while I have shown and described the 55 preferred construction, combination and ar-

rangement of parts, I reserve the right to make such changes as properly fall within the spirit and scope of the invention as claimed.

Having thus described my invention, what 60 I claim and desire to secure by Letters Patent, is:

1. In a curtain fixture, a main bar having elbows at its ends, brackets associated with said elbows and provided with notched supporting members, and a supplemental bar having lips at its ends to interlock with the notched portions of said supporting members. 65

2. In a curtain fixture, a main bar having 70 elbows at its ends, brackets mounted in said elbows for carrying said main bar and provided with notched supporting members, and a supplemental bar having hollow terminals 75 to receive said supporting members and provided with lips for interlocking with the notched portions of said supporting members.

3. In a curtain fixture, a main bar having 80 elbows at its ends, supplemental bars associated with said elbows, means for supporting the ends of the main bar, and a supporting element having spaced seats open at their upper ends to receive and support the main and supplemental bars intermediate 85 their ends.

4. In a curtain fixture, a main bar consisting of telescopic sections having frictional means for holding them at any point of their adjustment and each section having an 90 elbow at its outer end with a socket therein, brackets removably fitting within said sockets and provided with notched interlocking members extending at right angles thereto, and supplemental bars consisting of telescopic sections having hollow rectangular outer terminals to receive said interlocking members and lips for entering the notches in 95 said members.

5. In a curtain fixture, a bar having elbows at its ends and consisting of telescopic sections, brackets mounted in said elbows and having inturned blades adapted to be slipped between a casing and a wall to which 100 said casing is secured, and clamps slidably 105 mounted in the elbows and adapted to engage the face of the casing and thereby coact with the blades in supporting the bar.

In testimony whereof I affix my signature. JOHN S. WRIGHT.
